UNITED STATES PATENT OFFICE.

GEORGE HADRICH, OF HIGHLAND PARK, MICHIGAN, ASSIGNOR OF ONE-THIRD TO THEODORE C. BETZOLDT AND ONE-THIRD TO MAXWELL W. BENJAMIN, BOTH OF DETROIT, MICHIGAN.

SPARK-PLUG.

1,345,765.

Specification of Letters Patent.

Patented July 6, 1920.

Application filed June 30, 1919. Serial No. 307,760.

To all whom it may concern:

Be it known that I, GEORGE HADRICH, a citizen of the United States of America, residing at Highland Park, in the county of Wayne and State of Michigan, have invented certain new and useful Improvements in Spark-Plugs, of which the following is a specification, reference being had therein to the accompanying drawings.

10 This invention relates to spark plugs for internal combustion engines having an ignition system adapted for producing sparks to detonate explosive mixtures in the cylinders of an engine, although spark plugs in accordance with my invention may be used in any chamber in connection with any electrical apparatus requiring jump sparks.

The primary object of my invention is to provide positive and reliable means, in a manner as hereinafter set forth, for producing a multiplicity of sparks in connection with a spark plug, so as to insure firing of an explosive mixture and an increase of the efficiency of an internal combustion engine equipped with the multiple sparking plugs.

Another object of this invention is to furnish a spark plug with a reciprocable electrode which may be held stationary during the operation of an engine to produce a multiplicity of sparks, or released so that the compression of an explosive mixture in an engine cylinder will cause the electrode to be shifted relative to the fixed electrode or body of the spark plug and thus remove carbon and other impurities that may retard the action of the spark plug and detract from its efficiency as a multiple sparking device.

40 A further object of this invention is to provide a spark plug with a two part or sectional insulator which facilitates the assembling of the parts of the spark plug, and provision is made for safely holding the insulator so that excessive pressure or heat cannot crack or injure the insulator body.

50 A still further object of this invention is to provide a spark plug having a fixed electrode presenting a plurality of teeth or spark protuberances and a movable electrode having similar teeth or spark protuberances

adapted to mesh with the teeth of the fixed electrode to remove carbon therefrom and clean the teeth so as to expedite sparking when said electrodes are included in an electric circuit.

The above objects are attained by a mechanical construction that will be herein-after considered and then claimed, and reference will now be had to the drawing, wherein—

Figure 1 is a vertical sectional view of the spark plug;

Fig. 2 is a horizontal sectional view taken on the line II—II of Fig. 1;

Fig. 3 is a horizontal sectional view taken on the line III—III of Fig. 1, and

Fig. 4 is a similar view taken on the line IV—IV of Fig. 1.

In the drawing, the reference numeral 1 denotes a metallic spark plug body having the inner or lower end thereof reduced so as to provide an annular interior lateral shoulder 2, and the reduced end 3 of the body is exteriorly screwthreaded so that it may be screwed into a cylinder or chamber wall, as is the usual practice in connection with an internal combustion engine. The reduced end 3 of the body 1 terminates in a nose or inclined wall 4 and diametrically opposed portions of said wall are cut away, as at 5 and the remaining wall portions formed with teeth or spark protuberances 6, the teeth being equally spaced and somewhat V shape in horizontal section.

The upper or outer end of the spark plug body 1 is interiorly screwthreaded, as at 7, to receive a gland or nut 8 having a central opening 9.

In the spark plug body 1 on the annular shoulder 2 thereof is a gasket packing ring or cushion member 10 and seated thereon is an annular flange 11 of an inner insulator 12. The inner insulator has a longitudinal bore 13 that is rectangular in cross section and the lower end of said insulator terminates in a nose 14 provided with a central recess 15. The upper or outer end of the insulator 12 also has a recess 16 in which is placed a bushing 17 having a rectangular opening alining with the bore 13, the purpose of which will presently appear.

On top of the inner insulator 12 and the flange 11 thereof are gaskets, packing rings or cushion members 18 and 19, the former bearing an annulus about the upper end of the inner insulator and the latter seated on the bushing 17 and provided with an opening registering with the opening in said bushing. Engaging the gaskets 18 and 19 is the inner end of an outer insulator 20 which extends through the opening 9 of the gland 8, said insulator having its inner end recessed to receive the upper end of the inner insulator 12, also to provide an annular shoulder 21 for a gasket, packing ring or cushion member 22 interposed between said shoulder and the inner end of the gland 8. The inner end of the outer insulator 20 has diametrically opposed vertical grooves 23 into which protrude pins 24 carried by the metallic spark plug body 1, said pins preventing rotation of the outer insulator 20 within the spark plug body 1.

The outer insulator 20 has a longitudinal bore 25 and the inner end of said bore is reduced and in axial alignment with the bore 13 of the inner insulator 12. The reduced end of the bore 25 affords a seat for a gasket, packing ring or cushion member 26 and seated on said member is a collar 27 of a movable electrode 28, said electrode being rectangular in cross section and extending from the outer insulator 20 through the bore 13 of the inner insulator with its lower end below the nose 4 of the body 1. The lower end of the movable electrode 28 is reduced to provide a rivet 29 adapted for holding a head 30 in operative relation to the nose of a spark plug body. The head 30 is cut away, as at 31 and the remaining portions thereof formed to provide teeth or spark protuberances 32, similar to the teeth 6 and adapted to mesh therewith. The inner walls of the teeth 32 support a ring 33 and this ring will coöperate with the teeth 32 in providing a multiplicity of jump sparks between the movable electrode and the fixed electrode represented by the nose 4 of the spark plug body 1.

The upper end of the electrode 28 is cylindrical and extends into a socket 34 slidable in the bore 25 carried by the lower end of a rod 35, said rod having the upper end thereof screw threaded to receive a nut 36 engaging a cap 37 mounted on the upper end of the outer insulator 20.

In the socket 34 is a coiled compression spring 38 engaging the upper end of the movable electrode 28 and as shown in Fig. 1 it is possible for the movable electrode to reciprocate within the inner insulator 12, such reciprocation being produced by the compression of an explosive mixture in the cylinder of an engine. The compression of an explosive mixture will shift the head 30

toward the nose 4 and cause the teeth 32 to enter the interstices of the teeth 6, remove carbon from both sets of teeth and maintain the same clean so that sparks may readily jump between the movable and stationary electrodes. The head 30 is only shifted in one direction by gases under compression and shifted in the opposite direction by the expansive force of the spring 38, but this spring may be rendered inactive by adjusting the rod 35 until it seats on the collar 27, thereby holding the movable electrode 28 fixed relative to the nose 4 of the spark plug body 1. This is the relation of parts during the operation of an internal combustion engine and it is only when the spark plug needs cleaning that the rod 35 is raised to permit of the movable electrode reciprocating and ejecting carbon and other deposits from the teeth or spark protuberances 6 and 32.

It is thought that the operation and utility of the spark plug will be apparent without further description, and while in the drawing there is illustrated a preferred embodiment of my invention, it is to be understood that the structural elements are susceptible to such variations and modifications as fall within the scope of the appended claims.

What I claim is:

1. A spark plug having a fixed electrode, a reciprocable electrode, and means for holding said reciprocable electrode stationary, said fixed and reciprocable electrodes having teeth adapted to mesh when the reciprocable electrode is reciprocated relative to said fixed electrode.

2. A spark plug comprising a body providing a fixed electrode, an insulator in said body, a movable electrode in said insulator and having a head at the fixed electrode of said body, the head of said movable electrode and the fixed electrode of said body having teeth adapted to mesh when said movable electrode is shifted, and means in said insulator adapted for holding said movable electrode normally stationary with the head thereof in spaced relation to the fixed electrode of said body.

3. A spark plug comprising a body providing a fixed toothed electrode, an inner insulator in said body, an outer insulator on said inner insulator within said body, a movable electrode in said insulators having a toothed head in spaced relation to the fixed toothed electrode of said body, and means in the outer insulator adapted for holding said movable electrode stationary.

4. A spark plug comprising a body providing a fixed electrode, insulators within said body, a movable electrode in said insulators adapted to be shifted toward the fixed electrode of said body by the compression of gases in the inner end of said spark plug

body, means in one of said insulators adapted to shift said movable electrode away from the fixed electrode of said body, and means adapted to render the last mentioned means inactive so that said movable electrode will be held stationary and in spaced relation to the fixed electrode of said body.

In testimony whereof I affix my signature in the presence of two witnesses.

GEORGE HADRICH.
